UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

TYPEWRITING MACHINE.

Application filed May 2, 1924. Serial No. 710,528.

This invention relates to typewriting machines, and more particularly to ribbon-feeding devices used in connection therewith, in which the ribbon is fed past the printing position by a step-by-step, longitudinal movement imparted by a universal bar.

One feature of the invention provides for a light, simple and effective control for the ribbon-feeding elements, applicable in general to typewriting and analogous mechanisms, and by which the ribbon is positively drawn in either direction at will or remains quiescent if desired.

15 To accomplish this purpose the machine is provided with a ribbon-spool at each side, actuated by ratchets, operated by the universal bar.

20 The ratchet-feeding elements are controlled by a manually operable shift-bar arranged to render the ratchet-driving pawls associated with one of the ribbon-spoils inoperative, while the other opposite spool is operated to feed the ribbon, the shift-bar 25 operating to reverse the relative positions of the pawls when a change in the direction of the ribbon-feed is desired.

25 These two extreme positions of the shift-bar are maintained by a spring-detent, and provision is also made for an intermediate position of the shift-bar when both spools are to be rendered inoperative and cessation of ribbon movement secured, as during an interval when the type are being used for cutting stencils and similar work.

30 Other features and advantages will hereinafter appear.

In the accompanying drawings,

35 Figure 1 is a longitudinal sectional view taken approximately through the center of the typewriting machine, some of its parts, not relating to the invention, being omitted.

40 Figure 2 is a partial plan view, showing the universal bar and its connections.

45 Figure 3 is a plan view, showing the relative position of the ribbon-spoils and associated controlling mechanism as mounted upon the front carriage-rail.

Figure 4 is a fragmentary vertical sec-

tional view of the left-hand ribbon-spool, the 50 view being taken in a plane indicated by the line Y in Figure 3.

Figure 5 is a similar sectional view taken through the right-hand spool on line X-X of Figure 3.

55 Figure 6 is a fragmentary detail view of the lower end of the ribbon-spool shaft.

Referring more in detail to the drawings, the numeral 10 designates a series of key-levers as arranged in banks at the front of 60 the machine in standard keyboard formation. Each key-lever operates a bell-crank 11, pivoted at 12 on the machine-frame, in communicating motion, by a connection 13, to the type-bar 14, causing it to turn on its 65 fulcrum 15, and force the type from inoperative or rest position on the cushion pad 16, to printing position against the face of the platen 17.

These series of type-bars are suspended 70 from a type-segment 18 secured to the frame of the machine and having a groove in its rear face, adjacent the type-bars, to house a curved universal bar 19 provided with lugs 20 secured to corresponding lugs 21 formed 75 on the side edges of a carrier 22.

This carrier is guided at its forward end by a tongue 23, slidably mounted in a slot formed through the type-segment 18, and is provided at the rear with side arms 24 80 pivotally connecting with the arms 25 of a swinging member, in turn pivoted to the rear frame member of the machine, thus affording a substantially straight-line movement of the carrier 22 at a right angle to 85 the plane of the segment 18.

To maintain the carrier in normal position, a tension spring 26 is connected between a projection on the carrier and a fixed part of the frame, as 27, the spring urging the 90 carrier forwardly against a stop 28.

From the foregoing it will be seen that the movement of the type-bar to the printing position causes it to engage the universal bar 19 a little in advance of the impact of 95 the type against the platen, moving the universal bar rearwardly, thus actuating the carrier 22 and any parts mounted thereon.

The end plates 29 of the carriage-shift-frame are joined at the rear by a back plate 30 and are supported by pivots at the free ends of levers 31 and 32, pivoted in the machine frame, and which operate in the attainment of a substantially straight-line, up-and-down movement of the shift-frame, defined by stops 33 on the machine frame. This shift-frame is provided with runways 34, shown in broken lines in Figure 1, between which is carried anti-frictional bearings for longitudinal movement of the carriage and platen.

A bracket 35, fixed on the front face of the back plate 30, supports the pivotal end of a ribbon-vibrator lever 36, extending forward nearly to the rear face of the type-segment 18, where its free end is connected to a ribbon-carrier 37 slidably mounted upon a stationary type-guide 38 secured to the segment.

The vibrator-lever 36 is actuated by a toggle link 39 pivotally connected in a slotted lug 40 on the carrier 22 and arranged to raise the vibrator-lever 36 and ribbon-carrier 37, covering the printing field of the type each time the carrier is actuated by a type-bar.

The carriage end plates 29 are formed at their upper front edges with inreaching flanges 29' for supporting spool-cups 41 secured by screws. These spool-cups are assembled in paired relation, respectively right and left hand, each having side openings to permit passage of the ribbon, directed toward the printing position, the bottom walls of the cups projecting beyond the openings and having fixed pivots on which are mounted rollers 42 having conical faces to take up slack in the lower edge of the ribbon; a flange 42' at the upper, smaller diametered end of the roller preventing the ribbon from disengagement.

As shown in Figures 4 and 5, brackets 43 are secured to the inner faces of the end plates 29, the brackets having lateral inreaching lugs 43' in which are sleeves 44, their lower ends being shouldered to rest on the lower lug and revolvably held by screws 45 threaded axially into the ends of the ribbon-spool spindles 46 rotatable within the sleeves 44.

Secured to the upper ends of the sleeves 44 are arms 47 bearing against the faces of the upper lugs 43', and which act co-operatively with the screws 45 to prevent endwise movement of the sleeves.

The outer, free ends of the arms 47 carry spring-pressed, pivoted pawls 48 engageable with the teeth of ratchet-wheels 49 to cause their rotation in one direction, spring-pressed detents 50, pivoted on the spool-carrying frames, preventing reverse movement of the ratchet-wheels.

These ratchet-wheels 49 are rigidly fixed

on the spindles 46 and are provided with dowel pins 51 suited to enter openings in the heads of the ribbon-spools 52 when the spools are disposed on the upper extending ends of the spindles 46, to which they may be secured by thumb-screws threaded into the spindle ends.

In order to actuate the arms 47 and thus rotate the ratchet-wheels 49, metal bands 53 are clamped to the sleeves 44 adjacent the lower lugs 43' of the brackets, the extending end of each band being twisted and bent downward at a right angle to receive rearwardly-directed pivotally-fastened connection links 54.

From the foregoing, it will be understood that the elements 53 act in the manner of crank-arms, which, upon being actuated, transmit rocking motion to the sleeves 44 and arms 47, causing the pawls 48 to advance the ratchet-wheels and ribbon-spools in a winding-up direction.

As shown in broken lines in Figure 2, the type-segment 18 is secured to inwardly-extending arms 55, forming part of a frame, and also on these arms are fastened brackets 56 supporting pivotal levers 57 at each side of the segment, the inner ends of these levers being pressed against the rear edge of the universal bar 19 by tension springs 58 and their outer ends being suitably connected with the links 54, so as to permit the forward ends of the latter to move with the crank-arm elements 53 without binding.

Thus, when the universal bar 19 is moved to the rear, by impact of the type-bars, the levers 57 will transmit a forward motion to the links 54, rocking the sleeves 44 and associated pawls 48 a definite distance, and both pawls act in unison to rotate their respective ratchet-wheels and ribbon-spools in opposite or contrary feeding direction.

It is therefore necessary to interpose selective means to determinably shift the pawls 48 from operative to inoperative positions, and to the reverse, in order to release the paying-out spool from its pawl and detent when the opposite spool is being actuated in a winding-up direction by its feed pawl.

To accomplish this purpose, cam plates 59 are arranged to rotate freely upon the spindles 46, between the arms 47 and ratchet-wheels 49, these cam plates being formed with two cam faces 60 and 60', positioned and arranged to jointly cam the teeth of the pawls 48 and detents 50 out of the path of the teeth of the ratchet-wheels 49 by a slight rotary movement of the cam plates.

In addition to the cam faces 60 and 60', the cam plates are formed with arms 61 in which are fixed downwardly-extending pins 62, engaging in the slotted arms 63 of a shift-bar 64 slidably mounted upon the flat faces of pads 65 forming part of the machine rail 34', the shift-bar being guided

by slots 66 engaged by studs 67 riveted to the pads.

The shift-bar 64 is of irregular shape to clear operative parts of the machine (not shown), and at the right-hand end is provided with an upwardly-inclined extension 64', offset rearwardly at its end and carrying a fixed finger-knob 68 by which the shift-bar and its connections may be moved 10 lengthwise.

From this description it will be seen that the camming elements that control the ribbon-feeding pawls operate alternately, that is to say, when one cam plate releases the 15 pawl and detent associated with its corresponding spool to operate the same, the other cam plate has rendered the pawl and detent at the other spool inoperative, so that the spindle of the latter spool is free 20 to rotate relatively to its sleeve when the ribbon is fed by the movement of the former spool.

In order to lock these shifting devices in either of these two extreme positions, a 25 spring detent 69 is secured to the right-hand frame, the same co-operating with either of two spaced detent openings 70 in the adjacent end of the shift-bar 64.

An intermediate or neutral position of the 30 shift-bar is secured by engaging the detent 69 in the opening 71, midway between the openings 70, in which position all of the pawls and detents that control the ribbon-feed will be raised out of engagement with the teeth of the ratchet-wheels and correspondingly the ribbon will not be fed in either direction, the instrumentalities herein described obviously fulfilling the purposes of the invention.

40 Variations may be resorted to within the scope of the invention, and portions of the improvements may be used without others.

Having thus described my invention, I claim:

- 45 1. In a typewriting machine provided with a ribbon, a pair of spools for feeding said ribbon, a ratchet for each of said spools movable therewith, an oscillatory arm for each of said ratchets having a pawl thereon for imparting ribbon-feed movement to the corresponding ratchet, a detent for each of said ratchets for preventing reverse movement thereof, oscillatory cam-plates for said ratchets movable to cam said pawls and detents out of engagement with said ratchets, and a shift-bar connected to said cam-plates and manually movable from a position wherein both of said pawls and both of said detents are disengaged from said ratchets into selective positions wherein a selected one of said pawls and its corresponding detent are in operative position, while the other of said pawls and its corresponding detent are in inoperative position.
- 50 2. In a typewriting machine provided with a ribbon, a pair of spools for feeding said ribbon, a ratchet for each of said spools movable therewith, an oscillatory arm for each of said ratchets having a pawl thereon for imparting ribbon-feed movement to the corresponding ratchet, a detent for each of said ratchets for preventing reverse movement thereof, oscillatory cam-plates for said ratchets movable to cam said pawls and detents out of engagement with said ratchets, 55 a shift-bar connected to said cam-plates and manually movable from a position wherein both of said pawls and both of said detents are disengaged from said ratchets into selective positions wherein a selected one of said pawls and its corresponding detent are in operative position, while the other of said pawls and its corresponding detent are in inoperative position, and retaining means, releasable on the manual pushing of said shift-bar, for holding said shift-bar in any one of said positions.
- 60 3. In a typewriting machine having a fixed type-bar segment, the combination with a shift-frame, a front, lateral runway for anti-friction elements carried by said shift-frame and disposed in the rear of said type-bar segment, and two ribbon-spools carried by said shift-frame and rotatable about vertical axes, of mechanism for rotating said ribbon-spools in opposite directions, and instrumentalities for disconnecting, at will, either or both of said ribbon-spools from said rotating mechanism, said instrumentalities including a slidable, lateral bar supported on said front runway and extending from one of said spools to the other in the rear thereof, an integral arm extending forwardly from each end of said slidable bar at each side of said segment, said arms having slots adjacent their front ends, a cam-plate member coaxial with and underlying each of said spools and arranged for disengaging said rotating mechanism from said spools, and pins fast in said cam-members and extending downwardly for engagement in said slots.
- 65 4. In a typewriting machine, the combination of a main frame, a segment supported thereby, a carriage, a carriage-shift-frame movable relatively to said main frame and having a machine-rail thereon, type-keys, a pair of spools for feeding a ribbon, a manually-movable shift-bar between said segment and said rail, slidably mounted on said rail and having forwardly-extending arms terminating adjacent said spools, means connected to said arms for controlling the direction said ribbon is to be fed, a finger-piece on one of said arms adjacent one of said spools, and means operative on the actuation of one of said keys and co-operating with said spools to feed said ribbon in

one direction when said shift-bar is in one position and in the reverse direction when said shift-bar is in another position.

5. In a typewriting machine of the class described, the combination with a platen, typing instrumentalities, and a universal bar vibrated upon operation of each of said instrumentalities, of a ribbon-spool, a vertical downwardly-extending spindle for said spool, a rotatable sleeve disposed around said spindle, a ratchet-wheel rotatable about said spindle and positioned between the upper end of said sleeve and said spool, instrumentalities connecting said spool with said ratchet-wheel, instrumentalities including a pawl mounted on the upper end of said sleeve for driving said ratchet-wheel step by step, a crank-arm fastened adjacent the bottom end of said sleeve, and a lever-system connecting said crank-arm with said universal bar, whereby movement of the latter under action of a typing instrumentality will cause a step-by-step movement of said ribbon-spool.

25. 6. In a typewriting machine, the combination of a main frame, type-keys thereon, a sleeve, means supporting said sleeve for rotation, means operable on the actuation of one of said keys and acting at one end of said sleeve to oscillate it about its axis, a spindle rotatable in said sleeve, a spool secured to said spindle and arranged for receiving a ribbon thereon, means at the other end of said sleeve operable on the oscillation of said sleeve to impart ribbon-feeding movement to said spool, and means for rendering the second-mentioned means inoperative.

7. The combination with a typewriting machine having a universal bar, a carriage and a carriage-shift-frame including end members, ribbon-spool cups and spools disposable therein, of brackets on said end members, sleeves rotatable in the brackets, means operable on the actuation of said universal bar to oscillate said sleeves about their axes, spindles revoluble in said sleeves, said spindles passing freely through said cups to receive said spools, ratchet-wheels rigid with said spindles for driving the spools, arms rigid with said sleeves, pawls pivoted on the free ends of said arms to normally engage the teeth of said ratchet-wheels, detents preventing reverse movement of the wheels, and means for selectively disengaging the pawls and detents from either of said wheels.

8. In a typewriting machine, the combination of a main frame, type-keys thereon, a universal bar mounted for movement relatively to said main frame, means operable on the depression of a type-key to actuate said universal bar, a sleeve, means supporting said sleeve for angular movement, a crank-arm rigid with said sleeve, a link piv-

oted on said crank-arm, means operable on the actuation of said universal bar to reciprocate said link and oscillate said sleeve, a spindle rotatable in said sleeve, a spool secured to said spindle and having a ribbon thereon, means operable on the oscillation of said sleeve to impart ribbon-feeding movement to said spool, and means for rendering the third-mentioned means inoperative.

9. In a typewriting machine, the combination of a main frame, type-keys thereon, a universal bar mounted for movement relatively to said main frame, means operable on the depression of a key to actuate said universal bar, a sleeve, means supporting said sleeve for angular movement, a crank-arm adjustably secured to said sleeve, a link pivotally secured to said crank-arm, means operable on the actuation of said universal bar to reciprocate said link and oscillate said sleeve, a spindle rotatable in said sleeve, a spool secured to said spindle and having a ribbon thereon, means operable on the oscillation of said sleeve to impart ribbon-feeding movement to said spool, and means for rendering the third-mentioned means inoperative.

10. In a typewriting machine, the combination of a main frame, type-keys thereon, a universal bar mounted for movement relatively to said main frame, means operable on the depression of a type-key to actuate said universal bar, a sleeve, a bearing at each end of said sleeve, supporting said sleeve for angular movement, a crank-arm secured to said sleeve adjacent one end thereof and between said bearings, a link pivoted on said crank-arm, means operable on the actuation of said universal bar to reciprocate said link and oscillate said sleeve, a spindle rotatable in said sleeve, a spool secured to said spindle and having a ribbon thereon, means operable on the oscillation of said sleeve to impart ribbon-feeding movement to said spool, and means for rendering the third-mentioned means inoperative.

11. In a typewriting machine, the combination with a ribbon-spool having a vertical axis and arranged for having a ribbon wound thereon, and a ribbon-vibrator inclined rearwardly from the axis of said spool, of a conical guide-pulley rotatable about a vertical axis and arranged for guiding the ribbon from said spool to said vibrator in such a manner as to hold the lower edge of said ribbon from sagging.

12. In a typewriting machine, the combination with a platen, a shift-frame having a side member adjacent each end of said platen and a rearwardly-inclined ribbon-vibrator, of a ribbon-spool-cup mounted on each side frame, two vertical spindles carried by said frame, one positioned in the center of each of said cups, a ribbon-spool

mounted on each of said spindles for having a ribbon wound thereon, vertically-mounted, conical guide-pulleys arranged with their largest ends down for guiding said ribbon from said spools to said vibrator and keeping the lower edges of the ribbon taut enough to prevent sagging, an integral ear on the bottom of each of said cups extending ap-

proximately towards said vibrator, an upwardly-extending, vertical spindle fast in ¹⁰ each of said ears for receiving said conical pulleys, and a flange at the top of said pulleys arranged for retaining said ribbon thereon.

ALFRED G. F. KUROWSKI.
